UNITED STATES PATENT OFFICE.

EDGAR KNIGHT, OF BRIDGEPORT, CONNECTICUT, ASSIGNOR TO SOLOMON
P. STODDARD, TRUSTEE, OF NEW YORK, N. Y.

HASP-LOCK.

SPECIFICATION forming part of Letters Patent No. 292,323, dated January 22, 1884.

Application filed August 30, 1883. (Model.)

To all whom it may concern:

Be it known that I, EDGAR KNIGHT, of Bridgeport, county of Fairfield, State of Connecticut, and a citizen of the United States, 5 have invented an Improved Hasp-Lock, of which the following is a full, clear, and exact description, reference being had to the accompanying drawings, forming part of this specification.

10 My invention relates to a hasp-lock; and it consists in the devices hereinafter described, constructed and combined to operate as and for the purpose set forth.

Figure 1 is a front elevation of a hasp-lock 15 containing my invention. Fig. 2 is a vertical central sectional view of the novel parts of the same.

My improved hasp-lock is composed, primarily, of the shank or stem A, upon one extremity of which is cast or otherwise formed or fixed the wide portion B, constituting the lock-case. This portion B is recessed from the rearward side or face, and in the case thus formed is contained the lock mechanism, the 25 recess being closed upon the rear by a suitable plate. Any known and suitable lock mechanism may be employed, and, as no novelty is claimed therefor, the mechanism is not revealed in the drawing. The opposite end of 30 the shank or stem A is recessed from the rearward, as shown at C, and this recess is adapted to receive the head of a screw or bolt, D, as shown. A plate, E, or similar device, is provided to close this recess on the rear, as shown, 35 said plate having an opening, e, through which the shank of the screw or bolt passes, and in which opening said shank has more or less play, as shown, and said plate is so formed and arranged relatively to the depth of the recess 40 E and the size of the screw or bolt head that said head has more or less play between the wall of the recess and the said plate, as shown in Fig. 2. This plate E may be held in its place in any suitable manner, as by rivets or 45 screws passing through it and into the shank A, as shown.

Upon the extreme end of the device, beyond the lock-case B, is a deep recess, F, wholly closed upon the front or face of the device, and open upon the rear. This recess is

adapted to receive and wholly inclose the staple G, into which the bolt of the lock is adapted to be shot, as seen in Fig. 2. This staple is preferably formed with the angular flange g, by which it is seated in its place, it being 55 there held by the screws g', as shown, and the recess F is, as before stated, and as shown in Fig. 1, adapted to wholly inclose the staples, together with its flange and fastening-screws.

In mounting my hasp-lock upon a trunk, 60 box, door, or other place, the fastening screw or bolt D first has its head seated in the recess C, and there secured by the plate E, as described, and when a screw is thus used it may be driven home by a driver, which is passed 65 through a narrow slot, which may be cut in the front wall of the recess, as shown at e, the driver being thus enabled to engage the screw-head, and the entire hasp-lock turning with the screw in the driving home. The screw 70 should in this instance be so seated, finally, that when the lock is locked to the staple the slot e in the front or face of the hasp will not coincide with the slit, nick, or square in the screw-head. When a bolt is employed, the 75 head is similarly seated in the recess C, and the shank of the bolt then passed through the orifice provided for its reception, and the fastening-nut then applied.

My improved hasp-lock is thus constituted 80 with its exposed face and sides formed of a continuous and unbroken surface, wholly inclosing the lock mechanism, the fastening devices and the staple, and without exposing any of the bolts or screws employed to seat the device upon a box, trunk, door, or other place, 85 and hence the liability to having the lock forced by the removal of any of the fastening-screws is avoided.

The play of the hasp at the joint formed by 90 the recess C and the bolt or screw head D permits the recess F to be seated upon and unseated from the staple G.

The shank of the hasp is, if desired, recessed on the rear side throughout its length, 95 as shown at B', to permit the head of the fastening screw or bolt to be inserted therein and passed to its seat in the recess C.

What I claim as my invention, and desire to secure by Letters Patent, is—

1. In a hasp-lock, the hasp A, carrying the lock-case B, and rearwardly recessed at C to receive the head of the screw or bolt D, and provided with a plate, E, having orifice e, to retain the head of said screw or bolt in said recess, as and for the purpose specified.
2. In a hasp-lock, the hasp A, rearwardly recessed at B to receive the lock mechanism, rearwardly recessed at C to receive the head of the screw or bolt D, and provided with a plate, E, having orifice e to retain the bolt-head in said recess, and also rearwardly recessed at F to

receive and inclose the staple G, all as and for the purpose specified.

3. In a hasp-lock, the hasp A, rearwardly recessed at C to receive the head of screw D, and provided with a plate, E, having orifice e to retain said screw-head in said recess, and the slot e in the forward wall of said recess, as and for the purpose specified.

EDGAR KNIGHT.
